Patented June 21, 1921.

UNITED STATES PATENT OFFICE.

LOUIS L. KORACH, OF CHICAGO, ILLINOIS

WINDOW-CLEANING MECHANISM

1,382,000.

Specification of Letters Patent. Patented, June 24, 1884.

Application filed September 20, 1917. Serial No. 192,309.

To all whom it may concern:

Be it known that I, LOUIS L. KORACH, a citizen of the United States, residing in Chicago, in the county of Cook and State of Illinois, have invented certain new and useful Improvements in Window-Cleaning Mechanisms, of which the following is a specification.

10 This invention relates to that class of window washers which are adapted to be operated from the inside of a window, for washing or drying or cleaning the outer side of the window panes.

15 The principal object of the invention is to provide a simple, economical and efficient window washer.

A further object of the invention is to provide a window washer which is adapted to be mounted with facility and operated from the inside of the window in washing and drying or cleaning the outer sides of the window panes of windows of various dimensions.

25 Other and further objects of the invention will appear from an examination of the drawings, and from the description and claims.

30 In the accompanying drawings, which are made a part of this specification, Figure 1 is a view in side elevation of a window washer constructed in accordance with my invention and improvements and shows the same as it would appear in operation, and mounted in position between the lower edge 35 of a window sash and a window sill, and with the upper outer extremity of the window cleaning arm or tool-supporting member and lever mechanism shown in lowered position in full lines, and in raised position 40 in broken lines:

Fig. 2, a plan view of the mechanism shown in Fig. 1 with a portion of the tool-supporting mechanism at the upper extremity of the lever mechanism omitted;

45 Fig. 3, an enlarged detail plan view of the lever-operating gear mechanism, taken on line 3-3 of Fig. 1, this view

Fig. 4, a detail view in side elevation of the main supporting member, with the adjustable lever-supporting member mounted thereon, with parts broken away and other parts omitted; and

Fig. 5, an enlarged view in vertical section, taken on line 5-5 of Fig. 1, looking in the direction indicated by the arrows, and

Fig. 5, an enlarged view in vertical section, taken on line 5-5 of Fig. 1, looking in the direction indicated by the arrows, and

showing the main tool-holding member at the upper extremity of the levers in elevation, and the tool-supporting spindle in section.

In constructing a window-cleaning mechanism in accordance with my invention and improvements, I provide a main supporting member or base *a*, which is, by preference, of angular construction, and provided with an upper longitudinal flange *b* and a bottom longitudinal flange *c*, between which is slidably mounted an inwardly and outwardly longitudinally adjustable lever-supporting bracket or bar *d*, which is pivotally connected with and adapted to support the lever mechanism hereinafter described; and is also adapted to support the lever-operating mechanism, or rack, gear and gear-operating mechanism hereinafter more particularly described. The main supporting member *a* has depending arm portions *e* and *f* at or near its opposite extremities, and laterally projecting arms *g*, which may be on the depending arm or bracket member *e*, are adapted to extend over the upper surface of a window sill *h*, said arms *g* being, by preference provided with anti-friction rollers *i* rotatively supported, and adapted to roll on the window sill as the device is moved transversely of the window to any desired position, in the operation of cleaning a window. An adjustable supporting arm *j* is mounted at or near the outer end of the

mounted at or near the outer extremity of the main supporting member α , and is adjustably secured in position by means of a bolt k having a suitable nut thereon, the bolt k being mounted in a perforation in the part f and adapted to extend through an elongated slot m in the part j . An anti-friction roller n may be rotatively mounted at the lower extremity of the part j , as shown in Figs. 1 and 4, and is adapted to engage the outer portion of a window frame. A clamping screw p is mounted in the lower angular portion q of the depending arm e and is adapted to clamp and securely engage the under side of the sill to hold the main supporting member α in any position into which the latter is adapted to be moved or adjusted lengthwise of the sill or transversely of the window. The main supporting member α is provided with elongated slots r , through which extend adjusting screws s , which are in threaded engagement with the longitudinally adjustable sup- 110

porting member *d*, already described. Means is thus provided for securing the longitudinally adjustable member *d* in fixed relation to the main supporting member *a*, in 5 different adjusted positions. The main supporting member *a* is also, by preference, provided with a connecting or upwardly projecting hook *t* which is adapted to slidably engage a suitable horizontal supporting-rod 10 *u*. The rod *u* is adapted to be secured to a stationary support such, for instance, as the lower edge of a window sash *v*, by means of suitable clamps *w*, fixed to said rod at or near the opposite extremities thereof, 15 and provided with a clamping screw *y*, mounted in threaded engagement with a jaw of each clamp *w*, and adapted to engage one side of the stationary support or sash *v*, each clamping member *w* having an opposite jaw *z* adapted to engage the opposite side of the sash or support *v*. It will be readily understood that the clamps *w* are adapted to be clamped with equal facility to either the inner lower sash *v*, or to the 20 bottom of the outer upper sash 2 as desired. When the device is to be secured to the upper sash the latter is of course lowered, and the inner sash is raised.

The inwardly and outwardly longitudinally adjustable sliding member *d*, already described, is provided with bearings or sockets 3, 4, at or near its opposite extremities, in which bearings is rotatively mounted an operating shaft 5, which is provided 30 at one end with a crank 6 having a handle 7, which is located on the inside of the window when the device is in operative position. The opposite end or outer extremity of the longitudinally adjustable sliding member *d* 40 is provided with a bracket 8, the upper extremity 9 of which has a socket or bearing portion 10, and the lower extremity 11 of which has a lower socket or bearing portion 12, and a vertical rack 13 is slidably mounted in said sockets or bearing portions 10 and 12. This rack has a series of rack teeth 14 on one side thereof, and is, by preference, provided with side strips 15 on opposite sides of the rack teeth and adapted to form 50 shields or guides. (See Fig. 3.) A stub shaft 16 is rotatively mounted in a suitable bearing 17 in an arm portion 18 of the adjustable member *d*, already described, and a spur gear 19 is mounted in fixed relation to 55 said shaft and in toothed engagement with the teeth 14 of the rack 13. A beveled gear 20 is fixed to the opposite extremity of said stub shaft and is in toothed engagement with a similar beveled gear 21 fixed to the outer 60 extremity of the rotative main driving shaft 5, already described. It is obvious that the rotation of the shaft 5, by means of the crank 6, in one direction will cause the toothed rack to be moved upward, and that 65 the rotation of said shaft in an opposite direction will cause said rack to move downward. A series of operating levers is supported by the inwardly and outwardly adjustable bar or member *d*, already described, and operatively connected at the lower extremity of the lever mechanism with the toothed rack 13, and at the upper extremity of the lever mechanism with an upper vertically movable tool-supporting member 22. The tool-supporting member 22 is, by preference, so constructed as to comprise a pair of horizontal arms 23, and a pair of vertical arms 24 in rigid relation to the arms 23, all of said arms being secured in rigid relation to each other by means of a central block or 70 filler 25 and a perforated end member or block 26 between and at or near the extremity of the horizontal arms 23. The upper extremities of the vertical arms 24 are secured in fixed rigid relation to each other 75 by means of pin 27, and said vertical arms are each provided with an elongated vertical slot 28. The horizontal arms 23, and also the vertical arms 24, are spaced apart and a tool-supporting spindle 29 is slidably mounted in position to extend through the perforated end member 26, and between the horizontal arms 23, and is provided with a compressible spring 30 encircling said spindle and in engagement with a transverse pin 95 31 in the spindle. The spring 30 is thus adapted to press the tool-supporting spindle 29 in the direction of the window pane 32, and the tool-supporting spindle is provided with a suitable tool-engaging end portion 100 33, which is, by preference, tapered and adapted to engage and securely hold a similarly tapered socket portion or shank 34 of a tool 35. The tool thus removably mounted on the spindle 29 may be in the form of a 105 sponge or other similar element provided with a shank or supporting member adapted to be removably secured to the spindle 29, or in the form of a squeegee having a similar suitable shank adapted to be removably secured to the spindle 29. 110

The means for connecting the toothed rack 13 with the tool-holding member 22 comprises a set or series of pivotally connected operating levers and link mechanism, as already suggested. A lower or main supporting lever 36, formed by preference of a pair of parallel lever members or bars, is pivotally connected at its lower end with the lower extremity of the bracket 120 arm 8 of the bar *d*, by means of a pivot 37. Another lever formed of a pair of lever members or bars of suitable length, designated by the reference numeral 38, is pivotally connected at its lower or outer end 125 with and supported by the outer end of the lever 36, the opposite or upper end of the lever 38 being pivotally connected with the tool-supporting member 22 by means of a transverse pivot 39. A supplementary sup- 130

porting and guiding lever 40, formed by preference of a pair of lever members or bars arranged side by side, is pivotally connected at its lower end with the toothed rack 13, by means of a transverse pivot 41, located directly above and in parallel relation to the pivot 37; and a lever 42, formed of a pair of parallel lever members or bars, is pivotally connected at its lower or outer end with the upper or outer end of the lever 40, by means of a transverse pivot 43 which is directly over and in parallel relation to the similar pivot 44 which pivotally connects the adjacent ends of the levers 36 and 38 already described. The upper end of the uppermost pair of lever members or bars 42 are connected together and in vertically movable relation to the tool-holding member 22 by means of a transverse connecting and guiding pin 45 which is secured at its opposite ends to said bars, respectively, and extends through and is in sliding engagement with the walls of the elongated vertical slots 28 in the vertical arms 24, of the tool-holding member 22. A pair of links 46 which are of equal length and parallel, are pivotally connected at their lower ends with the tool holder 22 and the adjacent end of the lever 38, by suitable means, such, for instance, as the pivot 39, already described; and the upper ends of the said links are pivotally connected with the lever 42 at a point a short distance from the ends of the latter, by means of a transverse pivot 46'. A similar pair of links 47 are mounted in parallel relation to each other and pivotally connected at their upper ends with the rack 13 and the adjacent ends of the levers 40 by means of the pin 41 already described; and the opposite or lower ends of the links 47 are connected with the levers 36 by means of a transverse pivot 48, located in the same vertical plane with the pivot 46', already described. The levers 38 and 40 are pivotally connected by means of a transverse pivot 49 which is parallel with relation to the pivots 43 and 44, and located at the same distance from each of said last named pivots as are the pivots 48 and 41 from each other. The levers 36 and 40 are parallel; and the levers 38 and 42 are parallel. All of said levers and links are spaced apart as indicated in Figs. 2 and 3, and are all so connected that the upper extremities of the levers 38 and 42 move in the same vertical plane in which the lower pivoted ends or axes of the levers 36 and 40 are located. It follows as a matter of course, that the parts pivots 45, 39 and 41 all move upward and downward in the same vertical plane. The levers 38 and 42 are at all times in parallel relation; and the levers 36 and 40 are, likewise, always in parallel relation to each other in whatever position the working parts of the device may be while in operation.

The levers above described extend longitudinally in vertical planes which are at right angles or perpendicular with respect to the vertical plane in which the window panes to be operated upon are located. The desired strength and rigidity is thus afforded, and the window-cleaning tool is held yieldingly and with the desired degree of firmness, in engagement with the outer surface of the window pane to be operated upon, and is moved with facility into position to engage and operate in an efficient manner upon any desired portion of the outer surface of either the upper or lower window pane, as desired. The bar *d* is adapted to be adjusted inward or outward with respect to the window and with respect to the main supporting member *a*, so as to be in the most advantageous position when the window pane of the lower sash is to be cleaned or operated upon, as well as when the window pane of the upper sash is to be operated upon or cleaned. The compressible spring 30 serves to yieldingly press the tool against the window pane with the desired degree of firmness, with the parts in any position into which they are adapted to be moved in the operation of the device. In some instances the rod *u* may be dispensed with, and the device successfully operated without being connected with said rod, or with the sash by means of said rod or similar guiding member. When the rod *u* is not in use, the sill serves to guide the device while it is being moved to different positions transversely of the window.

The adjustable depending arm *j* is adapted to be adjusted to different positions to correspond with the outer surfaces of window frames or sills of various sizes and shapes, and serves to support the outer extremity of the main supporting member *a* in any position into which it is moved transversely of a window during the operation of the device.

The inwardly and outwardly adjustable bar or lever-supporting bracket member *d* is adapted to support the set of crossed levers in such position that each of the levers extends longitudinally in a plane perpendicular to the plane of a vertical window pane to be operated upon. In other words, the levers are supported in position to extend lengthwise and swing in a vertical plane at right angles of perpendicular with respect to the vertical plane in which the window pane to be operated upon is located.

In order to reduce the friction caused by the movement of the rack 13 to a minimum, anti-friction rollers 10' are provided, between which the rack is adapted to operate. It is obvious that the device constructed as above described is capable of being operated with the levers disposed in any de-

sired plane substantially perpendicular to the plane in which the surface of a window pane to be operated upon is located, although I prefer that the levers should operate in a vertical plane when the device is used for cleaning windows or panes of glass other than the wind-shields of automobiles or the like:

I claim:

10. 1. In a window cleaning mechanism of the class described, the combination of a set of pivotally connected levers comprising a lower pair of parallel levers pivotally connected with an upper pair of parallel levers, 15 links connecting the lever members of each pair of said levers, a supporting member pivotally connected with one of the lower levers and adapted to support said levers in position to extend in a plane at right angles 20 to the plane of a vertical window pane to be operated upon, lever-operating mechanism comprising a reciprocating member pivotally connected with the other of said lever levers at a point near its extremity, 25 means for operating said reciprocating member, and a tool-holding member upon and movable with the extremities of the upper pair of connected levers in a direction parallel to the path of movement of said reciprocating lever-operating member, said links being oblique to the length of said levers.
2. In a window cleaning mechanism of the class described, the combination of two pairs 35 of pivotally connected levers, links connecting the lever members of each pair of said levers, a supporting member pivotally connected with and adapted to support said levers in position to swing in a plane at right angles to the plane of a vertical window pane to be operated upon, a reciprocating lever-operating member pivotally connected with said levers at a point near the base of one pair of said levers, a tool-holding member upon and movable with 45 the free end of the other pair of said levers, means for removably securing a tool in position on the tool-holding member, and means for operating the reciprocating lever-operating member.
3. In a window cleaning mechanism of the class described, the combination of a pair of main supporting levers arranged in parallel relation, a stationary lever-supporting member pivotally connected with one of said pair of levers, a reciprocating lever-operating member pivotally connected with the end of the other one of said pair of main supporting levers, tool-supporting lever mechanism comprising a lever member pivotally connected with both of said first-mentioned pair of main supporting levers, a link pivotally connected with and forming a connection between said first-mentioned 55 pair of main supporting levers, said link being disposed in oblique relation to the length of said connected levers and operatively connected with said reciprocating lever-operating member, means for securing a tool in position upon the tool-supporting 70 lever mechanism, and means for operating the reciprocating lever-operating member.
4. In a window cleaning mechanism of the class described, the combination of two pairs of pivotally connected levers, links pivotally connected with and connecting the members of each pair of said levers, an adjustable supporting member pivotally connected with and adapted to pivotally support said levers in a position to swing in a plane perpendicular to the plane of a vertical window pane to be operated upon, means for removably securing a tool in operative position upon the lever mechanism, lever-operating mechanism mounted on said adjustable lever-supporting member and operatively connected with said levers, and means for securing said adjustable supporting member in operative position.
5. In a window cleaning mechanism of the class described, the combination of two pairs of pivotally connected levers, links pivotally connected with and forming a connection between the lever members of each pair of said levers, a supporting member pivotally connected with and adapted to pivotally support said levers in position to swing in a plane perpendicular to the plane of a vertical window pane to be operated upon, lever-operating mechanism mounted upon said supporting member and operatively connected with said levers, means for securing a tool in operative position upon the lever mechanism, and a stationary supporting member upon which said first-mentioned lever-supporting member is movably mounted.
6. In a window cleaning mechanism of the class described, the combination of two pairs of pivotally connected levers, links pivotally connected with and forming a connection between the lever members of each pair of said levers, an adjustable supporting member pivotally connected with and adapted to pivotally support said levers in position to swing in a plane perpendicular to the plane of a vertical window pane to be operated upon, means for securing a tool in operative position upon the outer pair of said levers, a rack reciprocatingly mounted upon said adjustable lever-supporting member and operatively connected with said levers, and means for operating the rack.
7. In a window cleaning mechanism of the class described, the combination of two pairs of pivotally connected levers, links 125 connecting the lever members of each pair of said levers, an adjustable lever-supporting member pivotally connected with and adapted to pivotally support said levers in a position to swing in a plane perpendicular to 130

1,382,000

5

the plane of a vertical window pane to be operated upon, a tool-holding member mounted upon and movable with the free ends of one pair of said levers, a reciprocating toothed rack mounted upon said adjustable lever-supporting member and operatively connected with said levers, shaft and gear mechanism in operative engagement with said rack, and a main supporting

member in supporting engagement with 10 said adjustable lever-supporting member.
